UNITED STATES PATENT OFFICE

CARL WILHELM MÜLLER, OF DRESDEN, GERMANY, ASSIGNOR TO THE FIRM "UNIVERSIELLE" CIGARETTENMASCHINEN-FABRIK J. C. MÜLLER & CO., OF DRESDEN, GERMANY

TOBACCO SPREADER FOR CIGARETTE MACHINES

Application filed September 7, 1929, Serial No. 391,061, and in Germany October 1, 1928.

The present invention relates to tobacco spreaders for cigarette machines.

While it is known in cigarette filling machines to introduce into a channel a definite quota of cut tobacco sufficient to form the cigarettes and to compress it by means of a plunger in order then to introduce the rod of tobacco of the right compactness into the cigarette paper case, the present invention is concerned with the preparation of the cut tobacco with a view to loosening it and uniformly distributing it for cigarette machines, so that the known plunger filling device can suitably be employed in conjunction with the apparatus of the present invention.

For the purpose in question it is customary to use so-called tobacco spreaders various forms of which have been proposed. Among other suggestions it has been proposed to feed the cut tobacco through a vertical channel to a take-up roller fitted with pins and arranged at the lower end of the channel, which roller rotates at uniform speed and co-operates with a suitably concentrically arranged extension of one channel wall in such manner that a uniform quantity of tobacco is delivered to a further pin roller on which the usual fleece is formed.

The problem of laying in the groove in the band conveyor which received the U-shaped tobacco strip leading to the cigarette machine a strip of tobacco which is uniform as regards quantity and density has hitherto not been satisfactorily solved.

The present invention offers a solution of this problem by providing for the reception of the tobacco prepared, loosened and already distributed by the known pin rollers and the take-up roller a broad channel of a width corresponding to the arriving fleece of tobacco, from which channel the tobacco is removed by pin rollers or the like operating at the end of the channel, in continuously uniform quantity, while a plurality of plungers arranged alongside one another act on the store of tobacco in the channel to compact uniformly the contents of the channel.

In this way a tobacco strip of considerable area is formed with certainty in the channel, which strip is uniform as regards the quan-

tity and density of the tobacco. If uniform quantities of tobacco be removed from this strip by means of stripper rollers, then there is delivered to the band conveyor a stream of tobacco which is of uniform properties as regards density and quantity, i. e., the problem is solved.

In lieu of plungers acting on the tobacco supply in the channel there may be provided a set of adjacent flexible pressers of steel or the like, so operated that they enter the channel at regular distances apart at its upper end, move downwards while being flexed, and then emerge from the channel.

By this arrangement uniform pressure is exerted on the tobacco supply in the channel, because the pressers are flexed in proportion to the resistance.

The invention is illustrated in the accompanying drawings in which Fig. 1 is a vertical cross section through the improved apparatus. Fig. 2 is a similar cross section with the parts in question in different positions. Fig. 3 is a vertical cross section through the channel. Fig. 4 shows a modified form of channel. Figs. 5 to 8 illustrate embodiments in which the plungers are replaced by resilient fingers, Fig. 5 being a vertical cross section through the apparatus, Fig. 6 a detail view from the side, while Figs. 7 and 8 show a modified form of presser in elevation and in plan view.

Referring to the drawings, the cut tobacco is located in a hopper 1 and is fed to the usual take up roller 5 in known manner by the band 2 forming the bottom of the hopper. The band passes over the rollers 3 and 4, its upper flight moving in the direction of the arrow. The pins of this roller 5 grip the tobacco and entrain a layer of tobacco which is regulated by the usual stripper roller 6 to the desired thickness. On the other side of the take-up roller 5 is arranged the usual pin roller 7, which with its pins enters the gaps between the pins on the roller 5 and removes the tobacco fibre from the roller 5. The tobacco fibres trickling downwards pass by way of the inclined shaker 8 into a hopper the rear wall of which is formed by the vertical

wall 9, the hopper having a discharge outlet 10 for the tobacco.

The discharge outlet 10 opens into a vertical channel, the front wall of which is indicated at 11 and the rear wall at 12. This channel, like the discharge outlet 10, is of the same breadth as the tobacco fleece, which corresponds to the length of the pin rollers 5 and 6. The spacing of the walls 11, 12 is such as to suit the quantity of tobacco arriving.

The front wall 11 of the channel, which may be in one with the inclined track 8, is mounted so as to be vertically movable. 15 Guide members 13 secured to the wall 11 of the channel and having vertical slots co-operate with guide pins 14 extending into the slots. The vertical movement is effected by bell-crank levers 15 which are mounted on 20 fixed pivots 16 and one arm of each of which is fitted with a roller 17 engaging the under side of a projection 18 on the wall 11, while the other arm is fitted with roller 19 tracking a cam 20 which is secured to the shaft 21 and 25 which rotates in the direction of the arrow. On each rotation of the cam 20, the levers 15 are rocked to lift the wall 11 of the channel as shown in Fig. 2.

The other wall 12 of the channel is carried 30 by rock levers 22, 23 which are pivotally connected to the upper and lower ends of the wall 12 at 24, 25 and therewith form a link parallelogram. The upper levers 22 are formed as bell-crank levers and the free end 35 of each is fitted with a roller 26 tracking the cam 27 secured to the shaft 28 and rotating in the direction of the arrow. On each rotation of the shaft 28, the levers 22, 23 are rocked and as a result the wall 12 is raised 40 and moved away somewhat from the wall 11 as indicated in Fig. 2.

The lower end of the front wall 11 is 45 pressed by a presser lever 29 against a shaped member or concave 30 which in conjunction with the pin roller 31 forms the lower closure 50 of the channel. The shaped member on the side nearest the pin roller 31 is arranged concentric with this roller and at a distance from the roller equal to the length of the pins. 55 The pin-roller 31 rotates in the direction of the arrow and co-operates with a second pin roller 32 so arranged that the tobacco fed forwards by the first pin roller 31 over the edge α of the shaped member 30 is fed by the roller 32 into the hopper 33, from which the tobacco passes on to the feed band 34 leading in the direction towards the cigarette machine into the U-shaped groove 35.

Adjacent to the upper end of the channel 60 are provided vertical plungers 36 disposed directly alongside one another, and shaped according to the width of the channel. These plungers are guided for vertical movement on the wall 9 and on the guide bars 37, 38.

65 Each plunger is provided on the rear side

with a projection 39, and with each projection 39 co-operates the bell-crank lever 40, one arm 41 of which carries a roller engaging the cam 42. A spring 43 maintains engagement between the roller and the cam. The cam 42 secured to the shaft 44 is rotated in the direction of the arrow. On each rotation of the cam 42, the relative plunger is raised, the roller 45 on the end of the actuating lever 40 engaging the under side of the projection 39.

Fig. 2 shows the raised position of the plunger 36. Each plunger is provided at its upper end with a further projection 46, which permits the plunger to be lowered only until the projection 46 rests on the guide bar 37.

The movements of the walls 11, 12 and of the plungers 36 are so controlled that with the plungers in raised position the opening 10 is free and fresh tobacco can pass into 85 the channel. At the same time the rear wall 12 is moved away somewhat from the front wall 11 for the purpose of releasing the tobacco, and at the same time the two walls 11, 12 are raised. Then the walls 11, 12 move towards one another and at the same time move downwards, so that the tobacco in the channel is pressed somewhat laterally and also moved downwards. Then the actuating levers 40 release the plungers 95 which bear with their weight on the tobacco in the channel. The plungers sink more or less dependent on the density of the tobacco in the different parts of the channel as is clear from Fig. 3. By means of the plungers the tobacco in the channel is given a uniform density, so as to ensure with certainty that at the lower outlet end of the channel the tobacco band of uniform quality will move into the path of the pin roller 31. 105 As this pin roller co-operates uniformly with the pin roller 32, a uniform quantity of tobacco of uniform quality must pass into the channel 33.

The weight of the plungers can be regulated to correspond to the properties of the grades of tobacco to be treated by making the plungers partly hollow at the upper end for the introduction of weights 47 or the like.

A modification is illustrated in Fig. 4 in which the two walls 11, 12 of the channel are not arranged for conjoint bodily reciprocation, but the rear wall can be raised somewhat. Over the adjacent faces of the inclined walls 11, 12 are led the flights 48, 49 of endless bands which pass around the guide pulleys 50, 51, 52, 53 and move in the direction of the arrow. These slowly moving bands grip the tobacco in the channel and feed the tobacco in the channel downwards in dependence on the speed of operation of the pin roller 31.

As seen in Figs. 5 and 6, in lieu of the plungers 36 adjacent to the channel 11, 12

there is arranged on the right hand side (see Fig. 5) of the channel a roller 54 mounted on the shaft 55. On the roller 54 are secured resilient tines of steel or the like which are bent as shown in Fig. 5 and which enter slots 57 in the side wall 11 and while being flexed press the tobacco downwards in the channel.

In the modification shown in Figs. 7 and 8 there are arranged adjacent to one another more or less elastic fingers 58 which are mounted on the supporting bar 59. This bar 59 is secured at both ends to the connecting rods 60 of two parallel crank drives. These parallel crank drives consist of discs 61 mounted on shafts 62 and set in uniform rotation by sprocket wheels 63 and chains 64. The crank mechanism is actuated by chains 65 which rotate uniformly the sprocket wheels 66 secured to the upper shafts 62. The action of the fingers 58 will be evident from examination of the circle shown in dotted lines which represents the line of movement of the foremost end of the fingers. The fingers thus enter the channel at the upper end, move downwards and again move outwards. Any particles of tobacco beneath the fingers are thus gripped and pressed downwards, the fingers of elastic material exercising mild pressure on the tobacco in the channel. Slots 67 are provided as in the embodiment shown in Figs. 5 and 6 by which the fingers pass through the walls 11, 12 into and out of the channel.

35 I claim:—

1. A tobacco spreader for cigarette machines comprising substantially parallel walls spaced apart and presenting between them a channel, means for distributing the tobacco on its way to enter said channel, means effecting movement of the tobacco along said channel, means for effecting continuous uniform withdrawal of tobacco from the delivery end of said channel, and movable elements disposed alongside one another responsive to the density of said tobacco for acting on the latter in said channel to compact uniformly the same passing through said channel.

50 2. A tobacco spreader for cigarette machines comprising substantially parallel vertical walls spaced apart and presenting between them a channel, means for distributing the tobacco on its way to enter said channel, means effecting movement of the tobacco along said channel, means for effecting continuous uniform withdrawal of tobacco from the delivery end of said channel, a set of plungers disposed alongside one another and adapted to act exclusively by their own weight on the tobacco in said channel to compact uniformly the tobacco passing through said channel, and means for lifting said plungers.

55 3. A tobacco spreader for cigarette ma-

chines comprising substantially parallel vertical walls spaced apart and presenting between them a channel, means for distributing the tobacco on its way to enter said channel, means for effecting up and down movement of said walls and moving said walls towards and from each other, means for effecting continuous uniform withdrawal of tobacco from the delivery end of said channel, a set of vertically movable plungers disposed alongside one another and adapted to act on the tobacco in said channel to compact uniformly the tobacco passing through said channel, and means for lifting the plungers during the movement of said walls away from one another.

4. A tobacco spreader for cigarette machines comprising substantially parallel vertical walls spaced apart and presenting between them a channel, means for distributing the tobacco on its way to enter said channel, conveyor bands extending lengthwise along said channel for effecting movement of the tobacco along said channel, means for effecting continuous uniform withdrawal of tobacco from the delivery end of said channel, and movable elements disposed alongside one another responsive to the density of said tobacco for acting on the latter in said channel to compact uniformly the same passing through said channel.

5. A tobacco spreader for cigarette machines comprising substantially parallel vertical walls spaced apart and presenting between them a channel, means for distributing the tobacco on its way to enter said channel, means effecting movement of the tobacco along said channel, means for effecting continuous uniform withdrawal of tobacco from the delivery end of said channel, a set of plungers disposed alongside one another and acting exclusively by gravity on the tobacco in said channel to compact uniformly the tobacco passing through said channel, said plungers being formed hollow to receive weights, and means for lifting said plungers.

6. A tobacco spreader for cigarette machines comprising substantially parallel walls spaced apart and presenting between them a channel, means for distributing the tobacco on its way to enter said channel, means effecting movement of the tobacco along said channel, means for effecting continuous uniform withdrawal of tobacco from the delivery end of said channel, and flexible pressers disposed alongside one another and movable into said channel, downwards in said channel and out of said channel, said pressers acting on the tobacco in said channel to compact uniformly the tobacco passing through said channel.

7. A tobacco spreader for cigarette machines comprising substantially parallel walls spaced apart and presenting between them a channel, one of said walls being slotted, means for distributing the tobacco on its way to

enter said channel, means effecting movement of the tobacco along said channel, means for effecting continuous uniform withdrawal of tobacco from the delivery end of said channel, a set of flexible tines disposed alongside one another and adapted to act on the tobacco in said channel to compact uniformly the tobacco passing through said channel, said tines being adapted to penetrate the slots in the slotted channel wall, and a rotary member carrying said tines.

8. A tobacco spreader for cigarette machines comprising substantially parallel walls spaced apart and presenting between them a channel, means for distributing the tobacco on its way to enter said channel, means effecting movement of the tobacco along said channel, means for effecting continuous uniform withdrawal of tobacco from the delivery end of said channel, resilient fingers disposed alongside one another and adapted to act on the tobacco in said channel to compact uniformly the tobacco passing through said channel, a bar carrying said fingers, two synchronously driven crank devices, and two connecting rods each connecting one crank device with one end of said bar.

9. A tobacco spreader comprising a channel to which tobacco is led, means for distributing the tobacco on its way to said channel, means for moving the tobacco along said channel, means for causing continuous uniform withdrawal of the tobacco from said channel and means to uniformly compact the tobacco passing through said channel, said last named means being responsive to the density of the tobacco for actuation thereon.

10. A tobacco spreader for cigarette machines comprising substantially parallel vertical walls spaced apart and presenting between them a channel to which tobacco is led, means for distributing the tobacco on its way to enter said channel, means for effecting up and down movement of said walls, means for effecting continuous uniform withdrawal of tobacco from the delivery end of said channel and movable means responsive to the density of said tobacco and acting on the latter in said channel to uniformly compact said tobacco while the latter passes therethrough.

In testimony whereof I affix my signature.

CARL WILHELM MÜLLER.
